Primary Examiner — Llorellys Martinez(74) *Attorney, Agent, or Firm* — Sughrue Mion, PLLC(57) **CLAIM**

The ornamental design for a bracelet, as shown and described.

DESCRIPTION

FIG. 1 is a top, front, and side perspective view of a bracelet showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side plan view thereof; and,

FIG. 7 is a left side plan view thereof.

The broken lines shown in FIGS. 1 through 4 and FIG. 6 illustrate portions of the bracelet that form no part of the claimed design.

1 Claim, 7 Drawing Sheets(56)
